UNITED STATES PATENT OFFICE.

CHARLES E. ARNOLD, OF INDIANAPOLIS, INDIANA, ASSIGNOR OF THREE-FIFTHS TO
GEORGE G. GRIFFIN, OF INDIANAPOLIS, INDIANA.

PRIMER FOR GASOLENE-ENGINES.

992,327.

Specification of Letters Patent. Patented May 16, 1911.

Application filed January 29, 1909. Serial No. 475,076.

To all whom it may concern:

Be it known that I, CHARLES E. ARNOLD, of Indianapolis, county of Marion, and State of Indiana, have invented a certain 5 useful Primer for Gasolene-Engines; and I do hereby declare that the following is a full, clear, and exact description thereof, reference being had to the accompanying drawings.

10 The object of this invention is to improve priming devices for gasolene engines. Heretofore measuring means have been provided in the priming tank, or in connection with it and remote from the cylinder of the 15 engine.

The chief feature of the invention consists in providing a valve for controlling the supply of gasolene to the engine for priming purposes, which valve measures, in a 20 way, the quantity of gasolene that is permitted to pass to the engine. During the throw or operation of the valve it temporarily opens a passage way for gasolene intermediate the limits of movement of the 25 valve, and during such temporary alinement of the port through the valve and the passegeway for the gasolene, a sufficient quantity of gasolene flows through the valve to the engine, to serve for the purpose of priming. By measuring the charge of gasolene with the valve, said valve or measuring device may be located comparatively near the cylinder of the engine and the gasolene stand normally close to the cylinder so that the 30 charge passes suddenly and almost directly to the cylinder, at least, to the intake pipe, so as to be immediately and completely drawn into the cylinder.

In carrying out the foregoing feature of 40 the invention a gasolene tank is mounted on the dash board of the automobile and a tube leads therefrom to short tubes connected with the intake pipes and the valve is located at the end of the tube leading 45 from the gasolene tank that lies nearest the cylinder of the engine, so normally the gasolene does not stand entirely in the gasolene tank but also in the pipe leading to the valve and, therefore, it stands normally 50 at the valve and ready to pass in on the instant the valve is operated.

Another feature of the invention consists in discharging the charge of gasolene for 55 priming purposes into the intake pipe and also having the tube from the carburetor

into the intake pipe so that air will be furnished through the carburetor to mix with the gasolene constituting the priming charge and the mixing will take place in the intake pipe.

Another feature of the invention consists in combining with the gasolene tank for priming purposes means for compressing air therein so that the gasolene will be normally under pressure sufficient to suddenly and 65 completely force the charge of gasolene through the valve, when it opens the passegeway, and no feature in the operation of the device is left to uncertainty or lack of 70 positiveness.

The nature of my invention will be understood from the accompanying drawings and the following description and claims.

In the drawing Figure 1 is a side elevation of the forward portion of an automobile with parts in section and other parts broken away. Fig. 2 is a central vertical section through the gasolene tank, the air compressor and the portion of the dash board to which they are secured. Fig. 3 is a side elevation of the measuring valve and the associated parts, showing the measuring valve in its unoperated position. Fig. 4 is a transverse central vertical section through Fig. 3. Fig. 5 is the same as the lower part 85 of Fig. 3 with the valve mechanism actuated. Figs. 6 and 7 are vertical sections through the lower parts of Figs. 3 and 5, but viewed from an opposite standpoint.

In the drawings herein 10 represents the 90 frame of an automobile, 11 the dash board, 12 the radiator, 13 the cylinders of the engines, there being four of them, and 14 the hood covering the engines. The cylinders of the engines are arranged in pairs, each 95 pair being connected by an intake pipe 15 so that there are in the drawing shown two such intake pipes. A pipe 16 runs from the carburetor 17 to said intake pipes. The connection between pipe 15 and 16 is preferably 100 about midway of the intake pipes as shown. On the dash board a gasolene tank 20 is secured for containing gasolene for priming purposes. There is also an air pump 21 secured on the rear side of the dash board and 105 in communication with the upper end of the gasolene tank whereby air may be compressed in said tank for forcing out the gasolene. A pipe 22 leads from the lower part 110 of the gasolene tank to a valve mechanism

23 mounted in connection with the middle portion of a pipe 24, below the hood, that connects with the middle of the intake pipes 15. Therefore, it is observed that the gasoline 5 stands under pressure in the gasoline tank and in pipe 22 right down to the valve mechanism and ready to issue through said valve mechanism when the valve permits it. Hence, this construction brings the gasoline 10 close to the cylinder of the engine, for as the valve mechanism is operated the charge of gasoline passing through will be immediately drawn to the proper cylinder according to the relative position of the piston in 15 the different cylinders, then the charge of gasoline is thus immediately thrown from the valve mechanism and drawn into the proper intake pipe where it at the same time mingles with air drawn from the carburetor 20 through the pipe 16. The gasoline and air which thus have entered the intake pipe mixes and immediately enters the proper cylinder.

While I have shown four cylinders the 25 invention is not limited to any particular number. The smaller the number of cylinders, the closer to the cylinders the valve mechanism 23 may be placed. Thus if there be only two cylinders the valve mechanism 30 would be located adjacent to the intake pipe 15.

Coming now to the construction of the measuring valve mechanism 23, it is in detail as shown in Figs. 3 to 7. A valve casing 35 which is secured to pipes 22 and 24 has a port or passage way 30 through each end thereof with which the ports 31 in the valve 32 are adapted to register at times. This valve is a four way valve tapering and fitting 40 snugly in the casing. It is actuated by the lever 33 with which a cord 34 is connected. During such actuation the ports register temporarily and then the gasoline passes 45 from pipe 22 through pipe 24 into the intake pipe, very suddenly. The registry of these ports is but for a moment. The valve is moved in the same direction at each operation thereof; therefore, on the end of the

valve there is a ratchet 44 with which a pawl 35 on the lever 33 is adapted to engage at 50 each operation of the lever, the lever returned to its normal position by the spring 36. The backward movement of the lever does not move the valve but merely moves the pawl into engagement with a successive 55 ratchet tooth in order that the valve may be given another partial revolution. Hence, the valve movement is step by step, herein having but one-fourth revolution at each actuation and stopping always with the ports 60 so that the conduit will normally be closed. The spring is a flat one fastened at one end to a pin 38 on the casing and at the other end to said lever. The return movements 65 of the lever are limited by a stop 39 on the casing.

What I claim as my invention and desire to secure by Letters Patent is:

1. The combination with a gasoline engine cylinder, of a conduit for supplying 70 gasoline thereto for priming, a rotary valve in said conduit provided with ports at intervals, and means for giving said valve a partial rotation at each operation thereof, whereby the valve will close the conduit at 75 the beginning and ending of each operation and will open the valve temporarily during the operation.

2. The combination with a gasoline engine cylinder, of a conduit for supplying 80 gasoline thereto for priming, a rotary valve in said conduit with a plurality of ports therethrough, a ratchet in connection with said valve with teeth corresponding with the ports, an oscillating lever for engaging 85 said ratchet and actuating the valve for a partial revolution, and a spring for returning said valve actuating means to its normal position.

In witness whereof, I have hereunto affixed 90 my signature in the presence of the witnesses herein named.

CHARLES E. ARNOLD.
